tion of New Jersey

Application February 2, 1949, Serial No. 74,086

17 Claims. (Cl. 177—329)

1

This invention relates to illumination apparatus and more specifically to a novel and improved structure for a red and white warning light. This invention further relates to a novel and improved method of controlling the apparatus of a warning light of the class herein described.

Although the present invention is to be understood as being of general utility, it may be pointed out that the structure shown herein and the method of control practiced thereby finds a particularly useful application as a warning light for vehicles such as railroad trains, or the like.

According to the present invention, illumination apparatus is provided comprising a source of light fixedly mounted upon a frame structure in such a manner as to come in beam projecting relationship with a rotatable parabolically shaped reflector. The reflector is provided with a suitable supporting structure having a driven connection with motor means mounted on another portion of the frame and is specially designed so as to have a color screen unit reciprocate through a generally axially disposed aperture defined by the reflector. The color screen unit is equipped with suitable reciprocating means so as to permit selective actuation of the unit to a forward color-screening position. When the color screen unit is in its forwardmost position, it surrounds the source of light, thereby providing for the production of a colored gyrating beam of light which is uniquely distinguishable within the range of visibility.

It may be noted that multi-colored gyrating lights have heretofore been provided; however, these lights have involved the use of an extremely cumbersome structure having intricate and involved mechanisms, or else have not been sufficiently rugged and reliable in use to permit wide spread use.

Thus, it is a particular object of this invention to provide a red and white warning light having a simplified construction which does not involve the unnecessary duplication of elements and which is convenient in operation.

A particular object of this invention is to provide a novel light employing a highly simplified electrical control system.

Another object of this invention is to provide a rotatable reflector defining a generally axially disposed aperture through which a color screen may be reciprocated for surrounding relationship with a bulb receptacle structure.

A further object of this invention is to provide a novel and improved color screen unit which

2

may be reciprocated upon a longitudinal axis in response to a change of rotational direction of a motor driving means.

5 A further object of this invention is to provide a red and white warning light which may be used as an emergency headlight for a vehicle such as a railroad train.

10 Another object of this invention is to provide a warning light which produces a gyrating beam of colored light in response to emergency conditions manifested through suitable actuating mechanisms.

15 Another object of this invention is to provide a method of control for a red and white warning light whereby an emergency condition, such as is manifested by the application of vehicle brakes, will cause the light to produce a gyrating beam of colored light.

Another object of this invention is to provide 20 a method of controlling a red and white warning light for a railroad locomotive whereby the light may project a fixed beam which may be selectively positioned along the circumferential path of its normal trajectory by means of an inching control.

25 Yet another object of this invention is to provide a method of control whereby a red and white warning light operating as an emergency headlight and projecting a stationary beam of white light will automatically start to rotate and produce a gyrating beam of colored light in response to predetermined emergency conditions.

Another object of this invention is to provide 30 a red and white warning light for railway vehicles which is economical to manufacture, convenient in operation, and efficient for its intended purpose.

Many other objects and advantages of the 35 instant invention will become manifest to those versed in the art through reference to the following detailed description and the accompanying drawings, in which:

Figure 1 is a side elevational view, partly in section, of an illumination apparatus incorporating the principles of my invention;

Figure 2 is a cross-sectional view taken on line II—II of Figure 1;

Figure 3 is an enlarged cross-sectional view taken on line III—III of Figure 2;

50 Figure 4 is a diagrammatic view showing the electrical circuit employed in connection with the present apparatus; and

Figure 5 is a diagrammatic view showing another electrical circuit which may be employed 55 in connection with the present apparatus.

Referring to Figure 1, an illumination apparatus indicated generally by the reference numeral 10 is shown as comprising a frame 11, a source of light 12, a reflector apparatus 13, a color screen unit 14, and a two-directional driving motor 15.

As may be seen on Figures 1 and 2, the frame 11 comprises a drum-type enclosure member 16 with which a drum housing cap 16a may be drawn up in firm surrounding assembly with a frame 11 by means of a knob 17 threadedly received upon a stud affixed to an upstanding support member 11a (Figure 2) of the frame 11. The frame 11 may take the form of a piece of wide bar stock bent in a U-shape as shown.

An end member 18 is also provided, which preferably takes the form of a ring-like casting having a socket mount 18a disposed on its diametric axis. The frame 11 is placed in firm assembly with the end member 18 as, for example, by bolts passing through suitable boss portions of the end member 18. The entire drum-type housing may be pivotally mounted as at 19 and may be further provided with adjusting means 20 for controlling the angle of tilt of the apparatus 10. Extending inwardly of the housing apparatus is a lamp shield 21 which may be secured in the socket mount 18a. A bulb 22 is provided which may be turned into a socket 22a centrally disposed within the shield 21.

Extending inwardly from the socket mount 18a and lying in spaced parallel relation above and below the receptacle 21 are a pair of guide rods 23, the utility of which will presently be explained.

Referring particularly to Figure 2, the color screen unit 14 is shown as comprising a colored glass globe 14a which, by way of example, may be understood as being made of transparent red glass, and a globe holder frame 14b. The globe holder frame 14b includes an annular end portion which may be suitably shaped to receive the globe 14a and a body portion which extends arcuately away from the end portion and terminates in a boss portion defining a cylindrical bore. A clamp plate 14c is firmly assembled with the end portion of the globe holder frame 14b and is provided with a pair of boss portions each defining a cylindrical bore.

Thus, it will be apparent that the globe holder frame 14b may be carried upon the guide rods 23 for sliding contact therewith whenever reciprocation of the colored screen unit occurs. A pair of resilient members 24 may be provided in surrounding relationship to the bosses of the clamp plate 14c and the guide rods 23 so as to permit a resilient shock absorbing contact between the socket mount 18a and the color screen unit 14 when the color screen unit is advanced to its forward position indicated by the dotted lines shown on Figure 2.

Referring further to Figures 1 and 2, the reflector apparatus 13 is shown, by way of example, as comprising a parabolic bowl-shaped reflector 13a. More specifically, the reflector 13a has an inner surface formed as a segment of a paraboloid of revolution. It should be noted that the reflector 13a defines a circular aperture which is disposed substantially on its center line axis. The reflector may be arranged to have its optic axis pass substantially through the lamp portion and may be situated so as to have the bulb 22 at the focal center of the reflector.

The reflector apparatus 13 is further provided with a reflector spider comprising a plurality

of arm portions 13b and a cup-shaped housing 13c which terminates on its closed end in a boss portion defining a cylindrical bore. The housing portion 13c of the reflector spider comes in substantially registered alignment with the aperture defined by the reflector, and the reflector 13a is rigidly mounted within the spider arms 13b.

As may best be seen on Figure 1, a mounting structure 25 in the form of an integral casting is rigidly assembled to the frame 11 and has mounted in firm assembly therewith the motor means 15.

A driven connection is provided between the reflector apparatus 13 and the motor means 15 in the form of a tubular drive shaft 26. Details of construction of the tubular drive shaft 26 are best seen in Figure 3.

The shaft 26 is substantially a cylindrical member having an enlarged diameter portion 26a at one end which is encased within the cylindrical bore in the boss of the reflector spider and locked in firm relationship therewith by means of one or more set screws 27 (Figure 2). The shaft 26 is further provided with a reduced diameter portion as at 26b. The enlarged portion 26a defines a partially threaded cylindrical bore terminating in a shoulder portion 26c. Seated within the bore and upon the shoulder 26c is a coiled spring 28 which is preferably selected to exert a spring bias of predetermined quantitative value.

Positioned adjacent the spring 28 and in abutting assembly therewith is a friction pressure ring 29. The ring 29 is annular in shape and is adapted to receive in threaded relationship therewith a stop screw 30, the head of which may project upwardly into a longitudinal slot formed in the enlarged portion 26a of the tubular shaft 26.

Thus it will be evident that the friction pressure ring 29 operates to confine the spring 28 within the limits prescribed by the longitudinal dimension of the slot in the enlarged portion 26a of the shaft 26, and the ring 29 will be reciprocable within the bore of the shaft 26 whenever a longitudinal thrust is exerted upon the ring 29 in sufficient quantity to overcome the bias of the spring 28.

A friction spinner member 31 of substantially annular configuration is positioned adjacent the ring 29 and within the bore of the enlarged portion 26a. The end of the bore of the shaft 26 is closed by a friction nut 32 which is provided with an externally threaded portion adapted to extend inwardly into the shaft 26.

A screw member 33 is disposed within the internal bore of the shaft 26. It will be noted that the diameter of the bore at the reduced diameter portion 26b of the shaft 26 is such as to support the screw 33, together with the friction pressure ring 29 and the friction spinner member 31 in correct radial alignment within the bore of the shaft 26. A deep thread, indicated by the reference numeral 33a, is cut upon the peripheral surface of the screw 33 and is preferably terminated at both ends of the screw 33 as at 33b. It will be understood, of course, that if continuously threaded screw stock is cut into lengths to form a plurality of screw members 33, the thread portions 33a may be terminated as, for example, by means of welding a stop plug into the ends of the open threads.

The friction spinner member 31 is provided with a thread following pin 34 which is normally seated in the thread portion 33a. Using the

planes of reference shown on the drawings, it will be apparent that if the shaft 26 is driven counter-clockwise, the thread following pin 34 will be in the position shown in Figure 3, and the shaft 26 will rotate freely while the screw 33 remains stationary.

However, if the shaft 26 is caused to rotate clockwise, a spring bias of predetermined strength exerted by the spring 28 will result in a thrust being imparted to the pressure ring 29 along a longitudinal axis of the shaft and will thereby urge the ring 29 into frictional engagement with the friction spinner 31. The friction spinner 31, in turn, will be thrust into frictional contact with the friction nut 32. Inasmuch as the spring bias exerted by the spring 28 is of a quantitative strength greater than opposition offered to the thread follower pin 34 by the screw 33, the friction spinner 31 will remain stationary with respect to its relationship to the friction nut 32 and the tubular shaft 26 and will therefore follow the helical path defined by the thread 33a of the screw 33.

The end result is that a longitudinal thrust is imparted to the screw 33 by means of the bearing engagement of the thread follower pin 34 against the side walls of the threaded portion 33a, and the entire screw 33 will move leftwardly until the thread follower pin 34 engages the stop portion 33b of the screw 33.

It may be seen on Figure 3 that the screw 33 is provided with a reduced diameter portion 33c which passes through the friction nut 32 and is seated within the bore defined by the boss portion of the color screen frame. Thus, whenever the screw 33 is actuated on a longitudinal path in response to a change in direction of the rotation of shaft 26, the color screw unit 14 is reciprocated through the aperture defined by the reflector 13a and is carried by the guide rods 23 to the forward position indicated by the dotted lines in Figure 2. When in the forward position, the colored globe 14a completely surrounds the bulb 22, thereby causing the beam of light reflected by the reflector 13a to assume the coloring of the globe 14a of the color screen unit 14.

It is also to be noted that inasmuch as the housing 13c of the reflector spider is fixedly assembled to the shaft 26, the reflector apparatus 13 will be rotated whenever the motor means 15 is in operation. As may be most clearly seen in Figure 1, the vertical axis of the reflector 13a is essentially perpendicular, thus the beam of light emanating from the bulb 22 and reflected by the reflector 13a will gyrate to define a circumferential path because of the angularly displaced axis of rotation relative to the optic axis of the reflector.

The shaft 26 may be supported in a conventional bearing structure 35 which is positioned upon the mounting structure 25 in firm assembly therewith. The tubular shaft 26 is maintained in longitudinal alignment with the bearing means 35 by means of an annular ring 36 adapted to surround the tubular shaft 26 in threaded assembly therewith and to abut the bearing means 35. The ring 36 may be locked upon the tubular shaft 26 by means of one or more set screws 37.

As may be seen in Figures 1 and 2, the motor means 15 more specifically comprises a prime mover 15a and a reduction gear box 15b. The shaft 26 is suitably coupled in driven connection with the reduction gear box 15b as is indicated at 15c (Figure 3).

It should be noted that the coupling 15c is pro-

vided with a centrally disposed aperture for receiving a snap switch impeller 38. The impeller 38 extends inwardly of the shaft 26 for bearing engagement with the end of the screw 33 and extends rearwardly through the reduction gear box 15b for bearing engagement with an actuating arm 39a of a snap switch 39. The snap switch 39 may be firmly anchored to the gear box 15b or to the upstanding portion 11a of the frame 11, as may be desired.

The operation of the snap switch 39 will be described in appropriate detail in a subsequent portion of this disclosure; however, it may be noted that when the color screen unit 14 is in its rearward position the screw 33 will bear against the impeller 38 in such a manner as to reciprocate the impeller through the bore of the coupling 15c in bearing engagement with the lever arm 39a of the snap switch 39. The switch operates in such a manner as to be automatically spring-biased to its closed position when not restrained by the impeller 38.

As may be seen on Figures 1 and 2, an enclosure member 56 is supported within the drum type casing by the frame 11 and the mounting structure 25 wherein the electrical devices about to be described may be contained.

Turning now to Figure 4, the electrical circuit and devices employed in carrying out my novel control method are indicated as including the bulb 22, the motor 15a, a motor field winding 15d for the motor 15a, a pilot light 40 associated with the motor 15a, and a series relay coil 41. It is assumed that the apparatus 10 is being used on a vehicle such as a railroad train or the like in connection with a usual locomotive headlight indicated by the reference numeral 50.

It is believed that the actual method of control of the instant apparatus will best be understood by tracing out and following a typical sequence of operational events as they occur.

Ideally the instant apparatus may be operated in accordance with several distinct operational phases as required by the nature of the installation. Thus, if installed on a railroad locomotive, it may be desirable to have the main headlight 50 energized and the apparatus 10 "gyrating white" during one phase of operation.

As may be seen on Figure 4, a two-position switch 42 is provided which, by way of example, may have its two positions indicated by the symbol "W" for "white" and "R" for "red." The switch 42 may be provided with a dimmer resistance 42b as shown. Assuming that the switch 42 is moved to the position "W," current will flow from the positive side of a suitable source of energy "S" through the switch 42 and into a lead a. Interposed in the lead a is a two-position relay switch 43 which, in the position shown, serves to electrically connect lead a to a corresponding lead a'.

For the sake of convenience, it is assumed that the lead a' conducts the current to a separate lead b in which is interposed the bulb 22. The lead b is electrically connected to another lead c connected to the negative terminal of the source S, thus the bulb 22 is energized and a beam of white light will be reflected by the apparatus. The beam of light may be selectively dimmed by manipulation of the switch 42.

Following the other extension of the lead b, it will be evident that further control of the apparatus resides in a series of switches identified as a manual switch 44, an itching control switch 45, and the snap switch 39.

It should be noted that the coupling 15c is pro-

By actuating the manual switch 44 to a closed position, current will flow from the lead *b* through the switch 44 and into the lead *d*.

Interposed in the lead *d* is a two-position relay switch 47 which, in the position shown, normally operates to conduct current from lead *d* to the lead *d'*. Thus, the motor 15a interposed in the lead *d'* will be energized. Current from the lead *d'* will return to the source *S* through a two-position relay switch 48 which, in the position shown, normally operates to electrically connect the lead *d'* with the lead *e* which, in turn, is connected with the lead *c*. It will be noted that the field winding 15d is interposed in a lead *f*. Thus, when manual switch 44 is closed, current will flow from the lead *d* into the lead *f* and back to the source *S* through lead *c*.

Another phase of operation of particular utility may be referred to as "gyrating red" operation. The selector switch 42 is actuated to the "R" position so current will flow from the source *S* into the lead *b* and to the series relay coil 41.

The series relay coil 41 is preferably of the type which is energized only when current flows therethrough in a predetermined direction, hence it will be evident that when the selector switch 42 is in the "R" position, the relay coil 41 will be energized. The relay coil 41 is actuatingly linked to the two-position relay switches 47, 48, 43 and a relay switch 49 in the headlight circuit, thus all of the two-position relay switches will assume their second position and the headlight circuit will be broken, extinguishing the headlight 50. It will, of course, be understood that the headlight is de-energized so as to make the red warning light all the more effective as a warning signal.

The bulb 22 interposed in the lead *b* will be energized. Current will also flow into a lead *g* connected to the lead *b* and through the two-position relay switch 43 into the lead *g'*. The lead *d* connected to the lead *g'* will then carry the current through the relay switch 47 and into the lead *d'* in a direction reverse from that previously established in "white" operation and back to the source *S* through the relay switch 48, the lead *e*, and the lead *C*.

Current from the lead *d* will also flow through the lead *f* through the field winding 15d and back to the source *S* in the same direction as before, thus it will be evident that the direction of rotation of the motor 15a will be reversed.

As has been previously set forth, a reversal of rotational direction of the motor 15a will cause the screw 33 to be actuated forwardly, thus reciprocating the color screen unit 14 relative to the reflector and the source of light into surrounding relationship with the bulb 22 to produce a beam of red light.

However, when the screw 33 moves forward, the snap switch 39 normally held open when the screw 33 forces the impeller 38 against the switch arm 39a, will snap to a closed position. Although the action of the switch 39 does not effect "red" operation, its significance will be explained presently.

The pilot light 40 interposed in a lead *h* will only be energized when the system is operating "red" by virtue of the current flow from the lead *d'* into the lead *h* and then back to the source *S*.

In order to operate the apparatus as an auxiliary headlight, it is only necessary to close the selector switch to its "W" position with the manual switch 44 left in the open position. However, in connection with this phase of operation,

it may be noted that the inching control switch 45 is of particular utility inasmuch as it will be apparent that the position of the reflector 13a relative to the light structure will result in the stationary beam of light being projected at a specific point on a circumferential path. The inching control switch 45 preferably takes the form of a push-button contact switch whereby the operator may selectively "inch" the reflector in rotation to direct the beam of light at any desired point on the circumferential path.

The inching control switch 45 permits current to flow from the lead *b* into the lead *d*, thereby energizing the motor 15a. Thus, the effective path of the auxiliary headlight beam may be adjusted to various locations on its rotational circumference as may be desired, for example, in rounding curves or in adjusting the beam on a portion of the roadbed.

The snap switch 39 serves to "normalize" the operation of the apparatus. For example, if the apparatus was used on "red" operation and then shut down prior to a subsequent operation as an auxiliary headlight, it will be apparent that in the absence of switch 39 the motor 15a would not be energized, and yet the color screen unit 14 would be in its forward position. However, since the snap switch 39 is automatically spring biased to its closed position when the color screen unit is in its forward position, re-energization of the apparatus, even for "stationary white," or auxiliary headlight, operation will cause current to flow through the switch 39 and into the lead *d*, thereby energizing the motor 15a. When the color screen unit 14 moves to its rearward position, the impeller 38 snaps the switch 39 open, thereby breaking the circuit and restoring the circuit to its normal operating position.

Turning now to Figure 5, a wiring diagram is shown illustrating how the instant apparatus may be arranged in a typical railroad vehicle installation and adapted for semi-automatic operation.

On the left-hand side of Figure 5 is shown a master switch 53. The positions of the switch are labelled "A" for "automatic" and "M" for "manual," although this designation is only for convenience inasmuch as the "M" position is frequently associated with normal night operations and the "A" position is frequently associated with normal day operations. The "off" position, in like manner, could be thought of as being suitable for yard service.

The switch 53 is shown in control of a circuit leading from a conventional 64-volt supply produced by the usual train generators. When in the "M" position, current will flow into a lead *j* to energize a motor-generator set 54.

Starting from the positive terminal of the generator, current will flow in a lead *k* to the selector switch 42a which corresponds to the switch 42 shown on Figure 4. Assuming, for the moment, that the selector switch 42a is in the "W" position, current will flow into a lead *l*.

A two-position switch 52 is interposed in the lead *l* and is controlled by a control device 54, which is herein shown as comprising a pressure responsive device suitably connected to the air brake conduits of the train. For purposes of explanation, it will be assumed that the switch 52 is in the position shown when the brakes are set.

Thus, if the train is operating normally, the switch 52 will be in its upper position, current

will flow through the switch 52 into the lead 1, which corresponds to the lead *a* of Figure 4, and the apparatus will be energized in accordance with the description of "white" operation aforesaid.

If the switch 53 is in the "A" position, the motor-generator set 54 will not be energized unless the control device 51 is actuated. If the device 51 is actuated, current will flow into the switch 53, through a switch 55 actuatable by the device 51, and into the lead *j* to the motor generator set 54.

Current will then flow from the generator into a lead *i*, through the switch 52 and into the lead *i'*, thereby energizing the apparatus in accordance with the description of "red" operation aforesaid.

In normal night operations, or if the apparatus is used in emergency operation as an auxiliary headlight, the master switch 53 will be at position "M," the selector switch will be turned to its "W" position, and the manual switch 44 will be opened or closed so as to produce a stationary or gyrating beam of white light. However, it may be desirable to automatically change the operation of the apparatus so as to produce a gyrating beam of red light when the vehicle, upon which the apparatus is mounted, is decelerated through the application of brakes preparatory to coming to a full stop.

To that end, the control device 51 and its associated switches incorporated into the wiring circuit are of particular utility. The device 51 may be of the pressure responsive type and may be arranged so as to be responsive to variations in the pressure of the air brake conduits, or may be of the inertia-type so as to be responsive to a predetermined deceleration.

As shown in Figure 5, when the control device 51 is actuated, current will flow from the generator into the lead *i*, through the two-position switch 52, and into the lead *i'*. Thus, the apparatus is automatically energized as for "red" operation and the color screen unit will be actuated to its forward position in response to the directional rotation of the motor 15a.

If the system is inadvertently shut down while the color screen unit is in the forward position, subsequent operation will be "normalized" by the snap switch 39, as before.

All of the wiring circuit on the right-hand side of Figure 5 corresponds to the circuit previously described with respect to Figure 4 with the exception of the manual switch 44 and the inching control switch 45. In Figure 5 these two switches are shown combined into a selectively operable switch 57. Other elements have been identified with like reference numerals for orientation purposes.

It will be apparent to those versed in the art that many modifications could be made to the instant apparatus without marking a departure from the spirit of my invention.

Although I have resorted to detail in the description of my invention for the sake of clarity, it is to be understood that my invention is not to be confined to the specific embodiment herein shown but I wish to be limited only by the scope of the appended claims and the prior art.

I claim as my invention:

1. A lamp unit comprising a lamp, a generally parabolic reflector having its optic axis passing substantially through said lamp with said lamp substantially at the focal center of said reflector, means for rotating said reflector selectively in either direction about an axis of rotation dis-

placed angularly with respect to said optic axis but intersecting said optic axis substantially at said lamp, said reflector having a centrally located opening through the back thereof, and a color screen mounted for reciprocation into said opening from a first position between said lamp and said reflector to a second position rearwardly of said reflector, means responsive to rotation of said reflector in one direction to move said color screen to said first position, and means responsive to rotation of said reflector in the opposite direction to move said color screen to said second position.

2. Illumination apparatus comprising, in combination, a frame, a bulb receptacle mounted on one end of said frame and extending inwardly thereof, a pair of rods secured to said frame in spaced alignment with said receptacle and extending inwardly in said frame in parallel relation with one another, a bulb in said receptacle, a parabolic reflector in spaced relation to said bulb for reflecting a beam of light outwardly past said bulb, said reflector defining an axially disposed aperture, a cup-shaped reflector housing, the open end of said housing being in registry with said aperture, said housing having spider arms extending therefrom for firm assembly with said reflector and defining a cylindrical bore at its closed end, a tubular shaft in said cylindrical bore and extending rearwardly of said housing, bearing means on said frame for supporting said shaft, motor means drivingly connected to said shaft, an annular pressure ring fixed in said tubular shaft adapted for limited longitudinal reciprocation therein, an annular friction spinner in said tubular shaft adjacent said pressure ring, spring means in said tubular shaft for spring biasing said ring toward said spinner, a screw engageable with said friction spinner and radially supported by said pressure ring in said tubular shaft, a globe retainer frame slidingly carried by said rods and reciprocatingly actuatable by said screw, and a colored globe in said retainer frame, whereby when said reflector is rotated in one direction a gyrating beam of white light is produced, and when rotated in the opposite direction said colored globe is reciprocated forwardly to surround said bulb thereby producing a colored gyrating beam of light.

3. Illumination apparatus comprising, in combination, a light source, a bowl-shaped reflector defining an axially disposed aperture and being in spaced relation with said light source, a cup-shaped housing firmly assembled with said reflector and adapted to come in registry with said aperture, a tubular shaft locked to said housing, a two-directional motor drivingly connected to said shaft, screw means reciprocable in said tubular shaft and through said housing, a globe support connected to said screw means, and a globe in said support, said globe and said support normally received by said cup-shaped housing, said screw means operable upon actuation of said motor in a reverse direction to reciprocate said globe through said aperture of said reflector into surrounding relationship with said light source.

4. In illumination apparatus, the improvement comprising, in combination, a reflector defining a centrally disposed aperture, a selectively operable two-directional motor, a driven connection between said motor and said reflector, said connection comprising a substantially cylindrical tube defining a longitudinal bore, a screw reciprocable in said bore of said connection, a friction spinner defining a tooth for engaging said

screw, an annular friction pressure ring loosely mounted in said bore, spring means in said bore adapted to spring bias said friction pressure ring toward said friction spinner whereby said screw may be reciprocated back and forth in said bore in response to a change in rotational direction of said motor and globe means connected to said screw, said globe means adapted to reciprocate through said aperture of said reflector.

5. In illumination apparatus of the type including a source of light and a rotatable reflector driven by motor means, a selectively actuatable color screen comprising, in combination, a frame, a screen in said frame, a driven connection for said reflector comprising a substantially cylindrical hollow tube, a friction nut for closing one end of said tube, a screw member axially disposed in said tube and extending outwardly of said friction nut for driving assembly with said frame, an annular friction spinner engageable with said screw and adjacent said friction nut within said tube, an annular friction pressure ring longitudinally reciprocable in a portion of said tube adjacent said spinner, and spring means in said tube adapted to exert a predetermined spring bias against said ring whereby said screw will reciprocate back and forth in said tube in response to the rotational direction of said driven connection for selective color screening of said illumination apparatus.

6. In illumination apparatus, the improvement comprising a source of light, a gyratable reflector positioned in spaced relationship to said source of light, said reflector defining an axially disposed aperture, means to gyrate the reflector and color screen means selectively reciprocable through said aperture into the region between said source and said reflector for screening said source of light whereby a selectively colored gyrating beam of light may be produced.

7. A red and white warning light apparatus and control circuit therefor on a movable vehicle, comprising, a motor generator set, an energization circuit for said motor generator set, a control device responsive to deceleration of said vehicle, switch means in said circuit controlled by said device for closing said circuit in response to deceleration of said vehicle, an illumination apparatus including a bulb, a rotatable reflector, a reciprocable rotation-responsive color screen unit and motor means, a circuit from said motor generator set, a first energization circuit for said apparatus, a second energization circuit for said apparatus, manual switch means for selectively energizing said first and second energization circuits, said manual switch means being interposed in said circuit from said motor generator set, a third energization circuit for said apparatus, automatic switch means in control thereof, said automatic switch means actuatable by said control device, said manual switch means operable to close said first circuit for energizing said bulb and said motor means as and for producing a gyrating beam of white light, said manual switch means operable to close said second circuit for energizing said bulb and said motor means as and for producing a beam of gyrating red light, said automatic switch operable upon a deceleration of said vehicle to close said third circuit for energizing said bulb and said motor means as and for producing a beam of gyrating red light despite the position of said manual switch.

8. In a control system for an illumination apparatus, including a source of light, a two-directional motor, a rotatable reflector and a reciprocable color screen unit selectively positioned

5 in response to the directional rotation of said motor, a first energization circuit for said source of light, a second energization circuit for said motor, a selector switch in control of said first and second energization circuits, and a manual switch in control of said second energization circuit, whereby said selector switch may be selectively actuated to close said circuits for two-directional energization of said motor and energization of said source of light and said manual switch may be selectively actuated to close said second circuit for intermittent energization of said motor.

9. A control system for an illumination apparatus including a source of light, a two-directional motor, a rotatable reflector having a driven connection to said motor and a reciprocable color screen unit selectively actuatable in response to the directional rotation of said motor, a selector switch, an energization circuit controlled by said switch, a relay means in said circuit actuatable in response to a predetermined directional current flow in said circuit, said source of light being interposed in said circuit, a manual switch, a motor energization circuit controlled by said manual switch and electrically connected to said first mentioned circuit, said motor being interposed in said motor energization circuit, switch means in said motor energization circuit actuatable by said relay means whereby current flow in said motor energization circuit may be reversed upon actuation of said switch means for reverse rotation of said motor, said manual switch being adapted for intermittent actuation whereby a stationary beam of light produced by said apparatus may be selectively inched along a predetermined path upon intermittent energization of said motor.

10. In a warning and signalling lamp unit, a generally bowl-shaped reflector having a centrally located opening through the back thereof, a socket in front of the curved portion of the reflector, a lamp carried by the socket having a filament projecting towards the reflecting surface of the reflector and being located substantially at the focal center of the reflector, means to gyrate said reflector to produce a changing pattern of light, and a color screen mounted for reciprocation from a first position rearwardly of said reflector through said opening and into a second position interposed between said reflector and said lamp bulb, and means for selectively moving said color screen to either of said two positions.

11. A lamp unit comprising an open-ended casing, an end member in the open end thereof, a socket in the end member, an incandescent lamp having a base portion in the socket and a bulb portion extending into the casing, a generally parabolic reflector having its optic axis passing substantially through said lamp with said lamp spaced from and disposed substantially at the focal center of said reflector, means for rotating said reflector about an axis of rotation displaced angularly with respect to said optic axis but intersecting said optic axis substantially at said lamp, said reflector having a centrally located opening through the back thereof, and a color screen mounted for reciprocation through said opening from a position interposed between said lamp and said reflector to a position rearwardly of said reflector, and means for selectively moving said color screen to either of said two positions.

12. Illumination apparatus for warning and signalling purposes comprising a light source, a

13

gyratable reflector spaced from said light source to reflect a beam of light past said light source, a reversible motor to gyrate said reflector for producing a changing pattern of light, a color screen to change the color of said beam of light and color screen control means to selectively move said color screen from an inoperative position into a color screening position, said color screen control means including operating elements responsive to a change in rotational direction of said motor, whereby the changing pattern of light will be colored in accordance with the direction of motor rotation.

13. A warning light comprising, in combination, a source of light, a motor, a rotatable shaft housing aligned on a substantially colinear axis with said source of light, said housing connected to said motor, a reflector mounted on said housing in a predetermined axial relationship relative to a horizontal plane and in spaced relationship to said light source to reflect a changing pattern of light, shaft means in said housing, control means responsive to said directional rotation of the motor to selectively reciprocate said shaft means in said housing, and color screen means connected to said shaft means, said color screen means being interposable between said light source and said reflector to selectively color the reflected light in response to the directional rotation of the motor.

14. A control system according to claim 8 in which a normalizing switch means is provided for the second energization circuit, said normalizing switch means adapted to be actuated by said reciprocable color screen unit in accordance with the relative positioning thereof.

15. A control system according to claim 9 in which a normalizing switch means is provided for the second energization circuit, said normalizing switch means adapted to be actuated by 40 said reciprocable color screen unit in accordance with the relative positioning thereof.

14

16. A warning light comprising a stationary light emitting source arranged to direct light rays in one direction, a rotatably movable parabolic reflector in spaced alignment with said source to collect and focus the directed light rays from said source into a beam of light projecting in an opposite direction beyond said source, means to selectively rotate said reflector in opposite angular direction to project a beam of light in a changing pattern of light, and color filter means selectively interposed between said source and said reflector in response to changes in direction of rotation of said reflector to color the directed rays of light, whereby the changing pattern of light is selectively colored.

17. In a warning light apparatus, a stationary source of light, a generally centrally apertured gyratable reflector spaced from said source of light, a motor having a driving connection with said reflector to gyrate said reflector to produce a moving beam of light, a cup-shaped color filter, and means to selectively move said cup-shaped color filter through the apertured reflector to substantially screen said source of light, whereby said reflector will reflect a colored beam of light.

ARTHUR C. HEEHLER.
